CLAIM

The ornamental design for a telecommunications terminal clip, as shown and described.

DESCRIPTION

FIG. 1 shows a front elevation view of a first embodiment of our new design;

FIG. 2 shows a cross-sectional elevation view thereof along the line 2—2 of FIG. 1;

FIG. 3 shows a right side elevation view thereof with the left side elevation view thereof being a mirror image of FIG. 3;

FIG. 4 shows a rear elevation view thereof;

FIG. 5 shows a top plan view thereof;

FIG. 6 shows a bottom plan view thereof;

FIG. 7 shows a cross-sectional elevation view thereof along the line 7—7 of FIG. 1;

FIG. 8 shows a front elevation view of a second embodiment of our new design;

FIG. 9 shows a cross-sectional elevation view thereof along the line 9—9 of FIG. 8;

FIG. 10 shows a right side elevation view thereof with the left side elevation view thereof being a mirror image of FIG. 10;

FIG. 11 shows a rear elevation view thereof;

FIG. 12 shows a top plan view thereof;

FIG. 13 shows a bottom plan view thereof; and,

FIG. 14 shows a cross-sectional elevation view thereof along the line 14—14 of FIG. 8.
